UNITED STATES PATENT OFFICE.

JESSE W. JOHNSON, OF INDIANAPOLIS, INDIANA.

DESIGN FOR A SIDE OR BRACKET FOR RADIATOR-SHIELDS.

No. 37,520.

Specification for Design.

Patented Aug. 29, 1905.

Application filed May 8, 1905. Serial No. 259,492. Term of patent 3½ years.

To all whom it may concern:

Be it known that I, JESSE W. JOHNSON, a citizen of the United States, residing at Indianapolis, county of Marion, and State of Indiana, have invented a new, original, and ornamental Design for a Side or Bracket for Radiator-Shields, of which the following is a specification, reference being had to the accompanying drawing, forming a part thereof.

The figure is a side view of a side or bracket for radiator-shields, showing my design.

I claim:

The ornamental design for a side or bracket for radiator-shields as shown.

JESSE W. JOHNSON.
